(57) CLAIM

We claim the ornamental design for a nose hair trimmer, as shown and described.

DESCRIPTION

FIG. 1 is a front perspective view of a nose hair trimmer of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a front perspective view thereof with the cap removed thereof.

The nose hair trimmer is shown with and without the cap for convenience of illustration.

The broken lines illustrate portions of the nose hair trimmer and form no part of the claimed design.
